CLAIM

(52) U.S. Cl. **D2/952**; D2/951; D2/953

The ornamental design for an outsole for a shoe, as shown and described.

(58) **Field of Classification Search** D2/902,

DESCRIPTION

D2/947, 951, 952, 953, 954, 956, 957, 958,

FIG. 1 is a bottom perspective view of a outsole for a shoe in accordance with the new design;

D2/960; 36/103, 22 R, 25 R, 32 R

FIG. 2 is a bottom view thereof;

See application file for complete search history.

FIG. 3 is a right side view thereof;
